UNITED STATES PATENT OFFICE.

CHARLES T. CARLSON, OF CANTON, OHIO.

DIE.

Application filed April 27, 1923. Serial No. 635,037.

This invention relates to die machines for forming sheet metal handles for saucepans and the like; and has for its objects to provide a machine including a beading die, in which blanks are fed and a forming or shaping die which automatically receives the partially finished product from the beading die and finally shapes the finished saucepan handle in continuous operations as the product is automatically passed through the machine.

The above and other objects may be attained by constructing a machine in the manner illustrated in the accompanying drawings, in which—

Figure 1 is a side elevation of the machine in the open position, the lower die being shown in section;

Fig. 2, a plan view of the lower dies;

Fig. 3, a section on the line 3—3, Fig. 1, showing the beading dies in closed or operative position;

Fig. 4, a section on the line 4—4, Fig. 1, showing the shaping dies in closed or operative position;

Fig. 5, a longitudinal section through the shaping dies, showing the same in closed or operative position;

Fig. 6, a plan view of the blank which is fed into the machine;

Fig. 7, a section on line 7—7, Fig. 6;

Fig. 8, a plan view of the blank after the beading operation;

Fig. 9, a section on line 9—9, Fig. 8;

Fig. 10, a plan view of the finished handle; and

Fig. 11, a section on line 11—11, Fig. 10.

Similar numerals refer to corresponding parts throughout the several figures of the drawings.

The lower dies are assembled upon the bed or base 1, which is mounted upon a suitable support and inclined at a considerable angle, as shown in Fig. 1. The forward or raised end portion of the bed is provided with the platform 2, upon its upper face, and the rear end of the body is provided with the longitudinal channel 3.

The lower beading or folding die includes a central, longitudinal rib 4 mounted upon the platform 2, and a pair of slideable, elongated blocks 5 mounted for transverse movement toward and from each other within the guides 6.

The blocks 5 are normally held in the

open position, in engagement with the posts 7, by means of the spiral springs 8 which are connected to the pins 9 upon the blocks 5 and to the pins 10 connected to the base or other stationary portion of the machine. 60

As best shown in Fig. 3, it will be seen that the inner edges of the blocks 5 are provided with the ribs 11 registering with the central rib 4 and with the half round longitudinal grooves 12 just above said ribs. 65 The outer longitudinal edges of the blocks 5 are chamfered or beveled as at 13 and transversely disposed guide plates 14 are fixed to the upper faces of the blocks and extend outwardly upon each side, being provided 70 with the guide openings 15.

The inner, longitudinal edges of the blocks 5, as shown in Fig. 2, are slightly inclined toward each other from front to rear of the machine, this being for the purpose of limiting the movement of the blank as it slides downward into position, the front end of the blank engaging the edges of the blocks 5 and being held in position to be beaded. 75

A channel-guide 16 is mounted at the forward end of the platform 2 and provided with the rearwardly tapered flanges 17 and the downturned outer lip 18, to facilitate the insertion of the blank shown at 19. 85 This blank is formed upon another machine which cuts the blank to the desired size and shapes and punches the opening 20 in one end thereof and bends the longitudinal edges upward at an angle as at 21. 90

The lower shaping die is mounted in the groove or channel 3 and comprises the forward portion 22 tapered downwardly and rearwardly toward the inclined channel portion 23 provided with the central, inverted V-shaped rib 24 which terminates in the substantially vertical shoulder 25, the rear portion 26 of the lower shaping die being inclined gradually upward and rearward from said shoulder and slightly 100 curved throughout its length, terminating in the upturned end 27.

Each of these parts of the die is preferably separable as best shown in Fig. 5, the several members being fixed in the channel 105 3 by means of a set screw 28 extended through the rear flange 29 of the base and engaging the rear end of the die. A knock-out punch 30 is preferably provided intermediate the ends of the lower shaping die 110

to automatically remove the finished handle from the die.

The upper or movable part of the machine includes the head 31 mounted for reciprocating motion toward and from the lower dies in a line perpendicular to the normal plane thereof and carries the upper clamping and shaping dies, which cooperate with the lower beading and shaping dies above described, as will be further explained.

The upper beading die includes the central rib 32 which is suspended from the under side of the head as by the hangers 33. A spaced pair of cam members 34 depending from the under side of the head 31 in position to engage the beveled edges 13 of the blocks 5 to slide the same transversely toward each other is shown in Fig. 3.

A pair of depending fingers 35 are carried by the head 31, between the cam members 34 and provided with enlarged head portions 36 arranged to be received through the openings 15 of the guide plates 14, to assist in moving the blocks 5 back to the normal position, as the head is raised.

The upper forming die comprises a block indicated at 37, the under side of which is shaped to conform to the upper surface of the lower shaping die, and is provided with a pair of spaced, depending plates 38 to cooperate with the V-shaped rib 24 of the lower shaping die.

A guide is formed to convey the partly finished product from the beading die to the shaping die, and comprises a pair of blocks 39 mounted upon the base beyond the beading die and provided with overhanging flanges 40 beneath which the blank is conveyed to the shaping die.

A guide lug 41 is mounted upon one side of the channel portion 23 of the lower forming die and upon the other side thereof is mounted a finger 42 provided with a set screw 43, arranged to remove the finished handle from the upper forming die in the event the handle adheres thereto when the upper die is raised.

In operating the machine, a blank 19 as shown in Fig. 6, is dropped into position through the guide 16 and between the blocks 5 of the lower beading die, the end of the blank engaging the inclined edge portions of the blocks.

As the head is depressed, the blocks 5 are moved toward each other by means of the cams 34, the bent edge portions 21 of the blank facilitating the folding or beading of the same as the die blocks are brought together as shown in Fig. 3, rolling or beading each edge portion of the blank as shown

at 44, forming the partly completed product 45.

As the head ascends, the die blocks 5 are moved back into the initial position by means of the springs 8, the fingers 35 assuring a positive movement of these blocks in the event the partly finished product should become wedged. As the product 45 is released, it will slide rearward and downward through the guides 38 until the end thereof engages the stop 46 of the lower shaping die.

With the next descent of the head 38, the upper shaping die will engage the blank and cooperate with the lower shaping die to form the finished handle 47 shown in Figs. 10 and 11, forming the angular end portion 48 for attaching the same to the sauce pan, and the reduced neck portion 49 having the reinforcing rib 50 for strengthening the same.

It will, of course, be understood that with each descent of the head two complete operations will be performed, as a blank will be beaded in the beading dies and the partly finished product will be simultaneously shaped into a complete handle in the shaping dies.

I claim:

1. A machine of the character described including a lower shaping die having a V-shaped channel portion provided with flat upper edges to receive a blank and an inverted V-shaped rib in the channel portion and a downwardly and rearwardly inclined portion and an upper die cooperating therewith and having a pair of spaced plates for engaging a sheet metal blank resting upon said flat edges to stretch the same over the rib and into the channel of the lower die, and an inclined portion to cooperate with the inclined portion of the lower die to form an angular end upon the finished product.

2. A machine of the character described including a stationary base and a movable head, a lower beading die carried in the base, an upper clamping die cooperating therewith and carried in the head, a lower shaping die in the base having a V-shaped channel portion provided with flat upper edges to receive a blank and an inverted V-shaped rib in the channel portion and an upper shaping die in the head cooperating with the lower shaping die and having a pair of spaced plates for engaging a sheet metal blank upon said flat edges to stretch the same over the rib and into the channel of the lower die.

In testimony that I claim the above, I have hereunto subscribed my name.

CHARLES T. CARLSON.
